UNITED STATES PATENT OFFICE.

CHRISTOPHER H. OLSON, OF DECATUR, ILLINOIS.

PINCHERS FOR SETTING BOX-CORNERS.

SPECIFICATION forming part of Letters Patent No. 278,262, dated May 22, 1883.

Application filed December 2, 1881. Renewed September 28, 1882. (No model.)

To all whom it may concern:

Be it known that I, CHRISTOPHER H. OLSON, a resident of the city of Decatur, county of Macon, and State of Illinois, have invented a certain new and useful Device for Adjusting Joint-Fasteners, of which the following is a specification, and which has never been patented to me nor to others with my knowledge and consent in any foreign country.

My invention consists in a pair of pinchers having its jaws bent at right angles to receive the joint-fastener, and the lower jaw provided with an offset for the proper adjustment of said joint-fastener.

In the drawings accompanying and forming a part of this specification, Figure 1 represents my device as operated, and Fig. 2 shows a joint ready to be "tightened up."

A is the pinchers, provided with jaws *a* *b*, bent as shown. B is the joint-fastener, held in position to be driven into piece C, which forms a joint with C' in Fig. 2.

In making a joint it is necessary to give the screw room to draw, and to accomplish this I construct the offset *c* in jaw *b*, which permits 25 the fastener to set in, as shown in Fig. 2.

In Fig. 2 the joint is not represented as complete, as the screw, when tightened, draws the fastener firmly against piece C'.

In operation the joint-fastener is placed in 30 the jaws, as shown, and the lower jaw used as a gage to determine the proper position of the points of the fastener, thereby making it possible to attach the same speedily and with accuracy.

I claim—

The pinchers A, provided with jaws *a* *b*, of unequal length, bent at an angle to the handles, and the longer jaw having an offset, as shown, and for the purpose set forth.

CHRISTOPHER H. OLSON.
